UNITED STATES PATENT OFFICE.

ANDREW J. ROZBORIL, OF PUEBLO, COLORADO.

BURGLAR-ALARM.

1,118,810.

Specification of Letters Patent. Patented Nov. 24, 1914.

Application filed April 19, 1913. Serial No. 762,272.

To all whom it may concern:

Be it known that I, ANDREW J. ROZBORIL, a citizen of the United States, residing at Pueblo, in the county of Pueblo and State 5 of Colorado, have invented new and useful Improvements in Burglar-Alarms, of which the following is a specification.

This invention relates to burglar alarms and more particularly to audible alarms 10 which are actuated in the opening of a door, window or other closure.

One of the principal objects of the invention is the provision of simple and efficient mechanism actuated upon the opening of a 15 window or door to explode a cartridge, whereby the impression will be given that the owner or occupant of the house is firing at the intruder.

Another and very important object of the 20 invention is the provision of a device of this character employing mechanism which includes a hammer and a trigger arranged in coacting relation so that the trigger will hold the hammer in cocked position or in 25 uncocked position removed from the cartridge, and whereby the hammer in uncocked position will hold the trigger out of the path of the sash or door so that either of 30 these parts may be operated without affecting the alarm.

Further objects of the invention will appear as the following specific description is read in connection with the accompanying drawing which forms a part of this application and, in which:—

Figure 1 is a plan view showing the parts in operative position; Fig. 2 is a side elevation of the same; Fig. 3 is a side elevation showing the arrangement of the parts with 40 the hammer in uncocked position; and Fig. 4 is a top plan view of the device shown applied to a window.

Referring more particularly to the drawings, 1 represents a base provided adjacent its ends with openings to receive attaching 45 devices 2.

In Figs. 1 and 2 the device is shown secured to the frame of a door in such position that the trigger will be operated upon opening of the door, while in Fig. 4 the device is arranged upon the upper sash of a window and with the trigger lying in position to be actuated upon the raising of the lower sash or the lowering of the upper sash. Formed 50 integral with the base is a raised cylinder member 3 and a lug 4 in which is journaled a

transverse shaft 5 having secured thereto the hammer or striking element 6 provided with a cap engaging pin 7 adapted to strike the cap of a cartridge 8 when operated, as 60 will be hereinafter described, the said hammer having an upwardly projecting arm 6' for a purpose to be hereinafter explained.

The cartridge is arranged in a diagonal bore 9 formed in a raised boss 10 immediately forward of the shaft 5. Extending through the cylinder member 3 longitudinally of the base is a shaft 11 having one of its terminals bent to provide a locking extension 12 and having its opposite end 70 bent at a point 13, to provide an operating trigger 14 which extends parallel with the extension 12. This trigger is adapted to lie over the arm 6' of the hammer and hold the hammer in depressed position against the 75 tension of the operating spring 15 which surrounds the shaft between the hammer and the lug 4 and is connected one end to each of these parts. In order to hold the trigger in depressed position there is secured to the base a small raised yoke 16 which is engaged by the offset end 17 of a spring 18 secured to the underside of the trigger, as shown.

In operation, the cartridge is placed in the bore 8 and the hammer depressed to the position shown in Fig. 2, against the tension of the spring 15. The shaft 11 is turned in the cylindrical member 3 by depressing the trigger 14 so as to carry the trigger over 90 the arm 6 of the hammer and to lock the spring 18 in engagement with the yoke 16. In this position the trigger is arranged over or in the path of the door or lower sash, as the case may be, and when either 95 part is open the trigger will be raised sufficiently to disengage the spring 18 from the yoke 16. When this is accomplished the tension of the spring 15 on the hammer will throw the trigger to one side and permit the hammer to forcibly engage the cap on the cartridge, exploding the same and sounding the alarm.

When it is desired to hold the parts in inactive position the trigger is raised and 105 the hammer allowed to swing over toward the cartridge for a predetermined distance. The trigger is then moved toward its operative position until the locking extension 12 is engaged in front of the hammer. In 110 this position the locking extension will hold the hammer out of engagement with the

cartridge and the hammer will hold the trigger out of the path of the door or sash, thus permitting either of these parts to be operated without sounding the alarm. In other words, the locking extension 12 practically holds the hammer at half cock and should the trigger be actuated the throw of the hammer would be so small and the striking force so light that the cartridge 10 would not be exploded.

What I claim is:—

A burglar alarm comprising a base plate having a firing chamber mounted thereon, a lug projecting upwardly from one side of the base plate, a cylindrical member mounted on the base plate and opposite the said lug and provided with a longitudinal passage therein, and a transverse passage underlying the said longitudinal passage, a shaft mounted transversely of the base plate and having its opposite ends journaled respectively in the lug and the transverse passage in the cylindrical member, a hammer fixedly mounted on the transverse shaft and 25 provided with a firing pin, and an arm arranged at an angle to the firing pin, a trig-

ger rotatably mounted within the longitudinal passage of the cylindrical member and having a laterally extending arm adapted to engage over the arm on the trigger when the latter is in full cock position and to terminally extend beyond one of the longitudinal edges of the base plate, said trigger having its opposite end bent into parallelism with the first mentioned end so as to 30 engage under the firing pin when the hammer is in half-cock position, a yoke mounted on the base plate, a spring mounted on the trigger and adapted to engage with the yoke to lock the hammer when the latter is 40 in full cock position and a spring on the shaft forcing the hammer in the direction of the firing chamber when the spring on the trigger is released from the yoke on the base plate.

In testimony whereof I affix my signature in presence of two witnesses.

ANDREW J. ROZBORIL.
